UNITED STATES PATENT OFFICE

WILLIAM F. OBERHUBER, OF LANSDOWNE, PENNSYLVANIA, ASSIGNOR TO FRANKLIN DEVELOPMENT CORPORATION, OF PHILADELPHIA, PENNSYLVANIA, A CORPORATION OF PENNSYLVANIA

SLUG FOR CLEANING CONDENSER TUBES

Application filed July 3, 1928. Serial No. 290,202.

My invention relates to slugs for cleaning condenser tubes and the like, with particular reference to cleaning slugs that present one or more engagement surfaces against the inside of the tube along a considerable portion of the length of the slug.

A purpose of my invention is to make slugs of the character indicated pass through the tubes more easily by applying a considerable portion of the transmitting force to the interior of the plug near the front of the plug in order to avoid or reduce longitudinal compression stresses in the material of the plug along the intermediate portions of the engaging surfaces.

A further purpose is to apply fluid driving pressure near the forward end of a plug that presents to the inside of the tube forwardly directed cleaning edges near the front and rear ends of the plug and of surfaces that engage the inside of the tube along a considerable portion of the plug length.

A further purpose is to provide a hollow plug with relatively staggered forward and rearward cleaning edges, with a fluid discharge at the forward and rearward edges, either or both, for carrying away loosened material from the interior of the tube ahead of the plug.

A further purpose is to mount a spring scraper upon the front end of a hollow slug so that the turns of the spring that engage the tube will be pulled forwardly rather than pushed forwardly.

A further purpose is to deliver a stream of driving fluid against the cleaning surface of a spring mounted upon a slug so as to carry away loosened matter from in front of the slug and to act as a fluid scrubber.

A further purpose is to provide a hollow rubber slug that has a larger hollow section near its forward end than at its rearward end, the thicker portion at the rearward end of the slug presenting a cleaning edge to the inside of the tube and having a greater sectional area to lessen the longitudinal compression stress in this portion of the plug incident to the forward push of the driving fluid exerted at the rear end of the plug.

A further purpose is to substantially limit

the compression stresses in the body of a slug to a rearward portion that presents a forwardly directed cleaning edge or edges against the inside surface of the tube.

Further purposes will appear in the specification and in the claims. 55

I have elected to show a few forms only of my invention selecting forms that are practical and efficient in operation and which well illustrate the principles involved. 60

Figure 1 is a side elevation showing one form of slug carrying a scraping spring. 65

Figure 2 is a left end elevation of Figure 1.

Figure 3 is an enlarged section taken upon the line 3—3 of Figure 2, with the spring removed. 65

Figure 4 is a left end elevation of the slug shown in Figure 1, with the spring removed. 70

Figure 5 is a section taken upon the line 5—5 of Figure 3. 70

Figures 6 and 7 are respectively a longitudinal side elevation and a longitudinal section of modifications. 75

Like numerals refer to like parts in all figures.

Describing in illustration and not in limitation and referring to the drawings:—

The slug shown in Figures 1 to 5 comprises a body 10 which is preferably solid rubber and a scraper spring 11 that is carried upon 80 a forwardly directed nose 12 of the body and may desirably be formed of spring bronze, either of round or square stock.

The outside of the body is shown presenting a uniformly cylindrical surface at 13 for 85 some distance from the rear end, and forwardly of the uniformly circular portion 13 as a longitudinally fluted surface in which arcuate surfaces 14, having the same radius as the surface 13, alternate with longitudinal flutes 15, the raised arcuate surfaces 14 tapering inwardly at 16 at the forward end of the main portion of the plug to the bottoms of the flutes. The cylindrical surface and the front end of the ribs constitute the scraper walls. 95

The forward inward taper 16 makes the insertion of the slugs into the ends of tubes more easy. Also when the plug is hollow the fluid pressure driving the plug through a tube expands the plug radially out against the in- 100

side of the tube, and may make the front edge of the taper portion a cleaning edge all the way around the plug circumference.

The body is hollow from the rear, and the 5 hollow portion has greatest area at 17 near the forward end of the main portion of the body of the plug, converging forwardly at 18 into the rear end of the nose 12 of the plug.

The extension of the hollow forwardly into

10 the nose of the plug adapts the forward end of the body at the taper portion to expand under the driving pressure inside the plug into substantial engagement with the inside of the tube, so that the front of the taper 15 portion may serve as a cleaning edge; and the converging end of the hollow presents a centrally registering seat to a finger, stick or other suitable implement that may be used to push the slug into the open ends of tubes.

20 I show the entrance portion of the hollow with a rearward flare 19. If desired this rearward flare may be omitted. It provides a saving in the amount of rubber required for each plug and makes the extreme rear end 25 of the plug adapted to easy radial expansion and contraction.

The rearward cylindrical portion 13 presents cleaning edges to the inside of a tube at 20 at the rear ends of the flutes.

30 The successive turns of the spring 11 converge forwardly and the forwardmost turn 21 has an interior diameter that is somewhat less than the external diameter of the portion 22 of the nose that carries the spring.

35 The nose 12 comprises step sections progressively smaller toward the front, the forwardmost section 23, having a diameter that readily passes the forwardmost turn of the spring and being used to pull the next section 22 through the forward turn 21 of the spring, the spring compressing the rubber somewhat.

The rearward end of the spring is bent radially inward and extended longitudinally 45 rearward into a suitable hole 24 in the front of the plug near the outer circumference of the rearward step portion 25 of the nose.

The spring is thus removably but strongly fastened to the plug by the circumferential 50 compression of the front turn of the spring into the rubber at 22 and by the seating of the rearward end of the spring in the hole 24.

55 It will be seen that the nose presents a shoulder 26 against the rearward side of the forward turn of the spring and that when the when the slug is passing through a tube the more rearward turns of the spring are in effect pulled forward by the forwardmost turn 60 21 which is in turn pushed forward by the shoulder 26.

The slug carrying the spring is conveniently pushed into the end of a tube by an implement engaging the front end of its interior 65 at 18, which stretches the spring longitudi-

nally, making it much easier to "enter" the slug.

One of the principal objects of my invention is to lessen heavy friction between the inside of the tubes and portions of the outside surfaces of the slug that are some distance rearwardly from the forwardly presented edges of the same surfaces.

I do this by lessening or preventing longitudinal compression stresses in the portion of the circumferential wall of the slug that is rearward of these edges, the cleaning action of the slug surfaces being most effective at the forwardly presented edges and least effective at portions of the surfaces that are rearward of the forward edges.

75 The engagement between the inside of the tube and portions of the slug surface that are relatively rearwardly distant from the cleaning edge has in the past made the slugs unduly hard to pass through the tubes without making their cleaning action better to any extent that is at all comparable with the greater fluid pressure needed to drive the slugs through the tubes.

80 When a slug is driving through a tube the forces acting upon it comprise driving forces effective across the area of the tube to force the slug along through the tube and resistive forces effective on the portion or portions of the circumferential surface of the slug that engages or engage the inside of the tube.

85 The total driving force upon the slugs is equal to the sectional area of the tube multiplied by the difference between the fluid pressure back of the slug and that ahead of the slug.

90 In the hollow slug shown in Figure 3 a major portion of this total driving force is applied inside the slug near the forward end 105 of the body portion, that is, upon that portion thereof that is in front of the largest diameter at 17, and as a result the longitudinal compression in the portion of the plug that is rearward of this diameter is diminished by 110 the presence of the hollow, by an amount that is equal to the force that is applied ahead of this diameter.

95 It will be seen that the area of the hollow portion will be increased somewhat by internal expansion due to the fluid pressure inside the hollow, and that this expansion results in compression radially outward against the inside of the tube, and this increase in sectional area may be quite material at the 115 forward end of the fluted section if, as in Figures 1 to 3, the raised portions forwardly taper.

120 The resistance presented by the inside of the tube to the outside of the slug will be offered wherever the slug presents contact to the tube, which is over the whole outside surface of the cylindrical portion 13, particularly at the forwardly directed cleaning edges at the front end of these portions 14,

and at the rearward turn of the spring 11 when the spring is used.

The rearward portion 13 of the slug will always be under longitudinal compression but the presence of the hollow greatly reduces this compression and by an amount dependent upon the sectional size of the hollow as compared to that of the tube.

The fluted portion ahead of the circular portion 13 may be either under longitudinal compression, longitudinal tension, or without longitudinal stresses of either tension or compression according to the relation between the resistance presented by the inside of the tube to the above different portions of the plug surface, and of the relation of the size of the hollow at 17 to the total area of the tube back of the plug.

In practice, I prefer to have the fluted portion of the plug ahead of the circular portion 13 under more or less longitudinal tension in order to more greatly reduce the tendency for the arcuate surfaces 14 to bulge along their length (particularly near the middle of their length) during passage through a tube, the tendency to bulge being due to friction along the length of the engaging surfaces with a heavy driving pressure applied to the plug rearwardly of these surfaces.

I provide the forward end of the plug with perforations 27 directed diagonally outward at the front end of the fluted portion of the body.

These perforations pass a stream of driving fluid which carries away loosened matter from in front of the plug, the fluid shooting through these perforations at a velocity greatly in excess of that of the forwardly moving slug.

When the condition of a tube is such as to make it advisable to use a spring, the driving fluid is usually water and the escaping streams of water from the perforations 27 serve not only to carry away the loosened particles from in front of the slug but also make the cutting action of the spring more effective.

In the form of Figure 6 I make provision for the passage of driving fluid along the outside of the slug by longitudinally fluting the exterior surface of the slug at 28.

The forwardly directed cutting edges 20' here extend directly across the rear ends of the flutes 15 of the forward portion of the slug, and I have not provided any inward taper on the front of the arcuate surfaces 14 (such as 16 of Figure 1) but have extended the hollow interior further rearwardly so that the largest diameter 17' of the hollow is but slightly to the rear of the cleaning end edges 29 presented by the forward fluted section.

With this arrangement the cleaning edges 29 at the front of the forward fluted section are pressed tightly against the inside surface

of the tube by the internal expansion from within the hollow, and the driving force back of this point is so small that the tube portion intermediate the cleaning scraping edges 29 and 20' is normally under longitudinal tension stress though under radial outward compression stress against the inside of the tube.

I have provided perforations 27' similar to the perforations 27 of Figure 3 so that driving fluid shoots out ahead of the moving slug, from both along the different flutes outside the slug and from inside the slug through the perforations 27', and very effectively carries away loosened particles from in front of the different cleaning edges.

I have made the forwardly converging end 30 of the hollow interior of the plug, substantially the same as in Figure 3 and when inserting these slugs into tubes, engage the slug at the axis at the front end of the hollow portion at 31 so that the plug is effectively pulled into the open end of a tube by reason of the push upon the hollow portion at 31.

When the slugs are driven through the tubes with compressed air they fly out the ends of the tubes and against the condenser wall that is normally in front of the tubes.

Hitherto they have struck the condenser wall head-on with a force that has injured the slugs to an extent that has materially shortened their life, and one of the objects of my invention is to avoid these injurious head-on impacts of the slugs against the condenser wall by making the forward end of the nose of the slug off center with respect to the slug axis.

The impacts are only injurious to any considerable extent if the slug strikes squarely upon its end, and in Figure 6 I have provided an offset nose that presents its forward end 32 well to one side of the central axis of the slug.

This forward end engages the wall of the condenser and deflects the slug laterally, preventing the squarely head-on impacts with the wall and in effect to great extent breaking the force of the impacts.

In this way I avoid the direct impacts in line with the axis of the slugs that have in the past resulted in shortening the slug life.

In Figure 3 I have made the hollow portion with uniform divergence from its section of minimum diameter to that of largest diameter at 17, while in Figure 6 I show the hollow as made up of two cylindrical portions 33 and 34, and the forwardly converging portion 30 that extends into the nose for proper registering the tool used for pushing the slug into the tube.

The exact form of interior is somewhat a matter of individual preference and ease of manufacture.

The longitudinal stresses in the circumferential wall around the hollow whether the

stresses are of compression or of tension, are in general less for a slug having a given maximum interior diameter where the radial wall is thick than where it is thin, in that the same total compression or tension force, is then carried upon a greater sectional area, therefore giving a lesser stress per unit area.

In the form shown in Figures 1 to 5 the spring 11 presents a scraping turn 21 that is in front of the forward end of the body portion of the slug.

Obviously I may have the spring present a plurality of turns in scraping engagement with the inside of the tubes and have illustrated this in Figure 7 where the spring 11' is mounted at its forward end upon the nose 12' in the same way as in Figure 1 but is provided with a plurality of turns 35, 36 and 37 which surround and are preferably radially spaced from the outside surface of a forward portion 38 of the slug.

The slug is provided with a wiper portion 13' which is generally similar to that shown in Figure 6 being provided with a cylindrical surface 39, having circumferentially spaced, longitudinally extending flutes or depressions 40 for the passage of water or other driving fluid to wash away particles loosened by the turns of the spring.

The portion 38 of the body of the slug that is surrounded by the rearward turns of the spring may desirably offer considerable resistance to radial expansion under the fluid pressure exerted inside the hollow portion of the slug, and may comprise rubber 41 lined with canvas 42 so as to be adapted to withstand the internal pressure inside the slug without stretching into direct engagement with the surrounding turns of the spring.

I show in Figure 7 the hollow as uniformly cylindrical from the rear end of the slug up to the section 17' at which it begins to converge forwardly into the nose of the slug and to the axis of the slug in order to properly centrally register any implement used to push the slug into the ends of the tubes.

It will be obvious that in all of the forms shown I prevent heavy engagement pressures with the tube at those portions of the wiping surfaces, the surfaces being such as to engage the tube along a considerable portion of the slug length, and do this by applying a major portion of the driving force upon the slug interior near the forward end of the slug.

In view of my invention and disclosure variations and modifications to meet the individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what

I claim as new and desire to secure by Letters Patent is:

1. A rubber slug having an external surface along a considerable portion of its length adapted to be presented against the inside of a condenser tube, and the slug being hollowed out from the rear, said hollow having a larger internal diameter near its forward end than near its rearward end and an internal area near its forward end greater than half the total sectional area of the slug, adapting the slug to receive a major portion of the driving pressure from the driving fluid effectively near the forward end of the slug.

2. A rubber slug having a body provided with forwardly directed cleaning edges near the rearward end of the body, other forwardly directed cleaning edges near the forward end of the body and an outer surface along a considerable portion of the slug length to make direct contact with the inside of the tube, and the body hollowed out from the rear, said hollow having a larger internal diameter near its forward end than near its rearward end and an internal area near its forward end greater than half the total sectional area of the slug, adapting the slug to receive a major portion of the driving pressure from the fluid back of the slug effectively near the forward end of the slug.

3. A rubber slug having a forwardly directed nose at its forward end, offset from the central axis of the slug.

4. A rubber slug hollowed out from the rear for a considerable portion of its length and a forwardly directed nose in front of the hollow, said hollow having a larger internal diameter near its forward end than near its rearward end.

5. A rubber slug presenting forwardly directed cleaning edges near its rearward end and other forwardly directed cleaning edges near its forward end, staggered with respect to the first named cleaning edges, the said slug having a forwardly extending hollow from the rear and perforations extending diagonally outward from near the forward end of the hollow to the forward side of the slug in front of the second cleaning edges.

6. A rubber slug presenting a succession of circumferentially spaced forwardly directed cleaning edges near its rearward end and other circumferentially spaced forwardly directed cleaning edges, staggered with respect to the first, near the forward end of the slug.

7. A rubber slug having a body presenting an external cylindrical surface that is fluted rearwardly from its forward end at circumferentially spaced intervals around the slug, the flutes not extending all the way to the rearward end so that the rearward ends of the grooves of the flutes provide forwardly directed cleaning edges near the rearward end of the slug, a nose comprising progressively smaller step sections from the forward end

of the body of the slug, a cleaning spring mounted upon the nose at an intermediate section, the forward turn of the spring compressing into the intermediate section and the turns of the spring extending rearwardly being successively larger, the rearward turn being adapted to engage the inside of the tube and having the end of the spring inserted into the body of the slug near the circumference, and the slug having a hollow from the rearward end to near the forward end.

8. A rubber slug for cleaning condenser tubes, hollow forwardly from its rear end to near its forward end and having a larger internal diameter near its forward end than near its rearward end.

9. A rubber slug for cleaning condenser tubes, forwardly hollow from its rearward end to near its forward end, and the hollow having a larger internal diameter near its forward end than near its rearward end and having a forwardly converging forward end.

10. A rubber slug for cleaning condenser tubes having longitudinally extending ribs, said slug being hollow from its rearward end to near its forward end, and the hollow near its forward end and in the neighborhood of the front ends of the ribs having a sectional area greater than half the total sectional area of the slug.

11. A rubber slug for cleaning condenser tubes hollow forwardly from its rearward end to near its forward end, and having, outside of the hollow, forward and rearward scraper walls, the hollow having a greater inside diameter at the forward scraper wall than at the rearward scraper wall.

12. A rubber condenser tube slug, hollow from its rearward end toward its forward end and having a spring mounted upon the front of the slug adapted to be dragged upon the front end of the slug but removable therefrom and engaging the walls of the condenser tube to the rear of the front end of the hollow in the slug.

13. A rubber slug presenting a succession of forwardly directed cleaning edges and forwardly directed fluid passages near the rearward end of the slug, and presenting a succession of other forwardly directed cleaning edges and intermediate water passages toward its forward end, the cleaning edges near the forward end being staggered with respect to those near the rearward end and the slug hollowed out from the rear, said hollow having a larger internal diameter near its forward end than near its rearward end so as to effectively apply the larger portion of the driving force near the forward end of the slug and longitudinal tension stresses between the forward cleaning edges and the rear end of the slug.

14. A rubber slug hollow from the rear to near the front end of the slug, a tubular

projection and a spring mounted upon the tubular projection and engaging the slug walls to the rear of the front end of the hollow.

15. In a water-driven slug for cleaning condenser tubes, a spiral cleaning spring, a hollow rubber slug connected with the spring at the front end of the slug and the smaller part of the diameter of the spring, the slug being apertured to deliver water in proximity to the line of engagement between the part of the spring of largest diameter and the condenser tubes to give a scrubbing action.

16. A composite slug comprising a rearwardly hollow rubber body adapted to seal against a tube at its rear end and having spaced ribs forwardly directed from said rear end and adapted to engage the tube and a forwardly directed nose at the front of the body in combination with a scraper having a forward end inwardly pressing into the nose and a flaring rear end presenting a scraping surface to the inside of the tube.
